UNITED STATES PATENT OFFICE

155,169

DESIGN FOR AN ELECTRIC SOLDERING
TOOL

Walter A. Kuehl, Chicago, Ill.

Application November 12, 1948, Serial No. 149,591

Term of patent 14 years

(Cl. D26—1)

To all whom it may concern:

Be it known that I, Walter A. Kuehl, a citizen of the United States, residing at Chicago, in the county of Cook and State of Illinois, have invented a new, original, and ornamental Design for An Electric Soldering Tool, of which the following is a specification, reference being had to the accompanying drawing, forming part thereof, wherein

Fig. 1 is a perspective view of an electric soldering tool, showing my new design;

Fig. 2 is a front elevational view;

Fig. 3 is a rear elevational view;

Fig. 4 is a top plan view thereof, the tip being broken away for convenience of illustration;

Fig. 5 is a sectional view taken along the line 5—5 of Figure 2, looking downwardly; and

Fig. 6 is a sectional view taken along the line 5—5 of Figure 2, looking upwardly and showing the handle portion of the soldering tool removed from the body.

I claim:

The ornamental design for an electric soldering tool, as shown.

WALTER A. KUEHL.
